UNITED STATES PATENT OFFICE.

ROBERT CARL RAHM, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

BRAIDING-MACHINE.

1,182,035.

Specification of Letters Patent.

Patented May 9, 1916.

Application filed August 8, 1914. Serial No. 855,751.

To all whom it may concern:

Be it known that I, ROBERT CARL RAHM, a citizen of the United States, residing at Wyomissing, in the county of Berks and State of Pennsylvania, have invented certain new and useful Improvements in Braiding-Machines, of which the following is a specification.

My invention relates to machines such as are commonly employed for producing braided fabrics and consists in an improved construction comprising a circularly grouped series of carrier courses which respectively overlap each other, and upon which several series of carriers are operated, as fully described in connection with the accompanying drawings, the novel features being specifically pointed out in the claims.

Figure 1 is a plan view indicating the main portion of a machine of the braiding type in which my invention is embodied in preferred form; the normal courses of the several series of carriers being shown. Figs. 2 and 3 are corresponding diagrammatic views indicating certain variations in the travel of the carriers upon the several courses as determined by operation of the switch mechanism provided. Fig. 4 indicates a piece of fabric of varying cross-section producible upon my improved machine. Figs. 5 and 6 are enlarged cross-sections on the lines 5—5 and 6—6 respectively of Fig. 4. Figs. 7 to 10 inclusive are diagrammatic views indicating how the relation of the stripes is varied.

The machine indicated in the drawings is a square stripe-braider, adapted to normally produce a fabric which is square in cross-section as indicated in Fig. 5; such braid being provided, when desired, with a central filler or warp, as is indicated at 2 in Fig. 5, though this filler may be omitted particularly in the special braiding of varied cross-section indicated in Figs. 4, 5, and 6.

The machine is provided with four similar carrier courses, marked respectively *a* *b* *c* and *d*, arranged in a linked series around a central plate-portion which is provided with an opening 5 adapted to serve as a filler or warp passage-way. Each of these

courses intersects two adjacent courses of the circularly arranged series of courses, at points 6—7, 6—7, and extends into them so as to form what I term overlapping portions 55 of the courses; each of said overlapping portions embracing, as indicated, two linking race-circles, 10^a, 10^a, of the respective intersecting courses, which circles may be cut out of said courses by carrier-switching means when desired.

Each of the courses *a* *b* *c* and *d* is provided with a series of carriers, marked respectively *a*¹ *b*¹ *c*¹ and *d*¹, which traverse their own courses only (Fig. 1) to produce 65 a product of square section such as indicated in Fig. 5; all of the carriers however being coöperatively driven as usual by a train of carrier drive gears 10, 10^a. The gears 10^a are so marked to distinguish them 70 as being located within the overlapping portions of the courses, and also as being provided with warp-thread openings 11, through which warp-threads adapted to serve as linking connections may be passed; 75 it being understood however that all of the gears may advantageously be provided with such openings so as to permit of employing filling warps when desired. The separate series of carriers operating upon adjacent 80 courses are respectively carried around such warp threads at 10^a, 10^a when the separate products of the different series of carriers are to be linked together in tubular form as indicated in Fig. 5; while warp threads 85 at other points may be utilized when the normal course of the carriers is changed, as hereinafter described.

In making a product of square section as indicated in Figs. 1 and 5, the several 90 series of carriers *a*¹ *b*¹ *c*¹ *d*¹ thus produce stripes forming the four walls of the fabric, upon their respective courses *a*, *b*, *c*, and *d*, while the warp threads which pass through the drive gears 10^a serve to link 95 together said walls at the four corners. To provide for giving greater body or strength to the fabric, a filler or core warp may be supplied through the central passage-way 5, around which filler the several series of carriers forming the inclosing walls will operate; additional filler or warp threads be-

ing introduced if desired, through any or all of the drive gears.

By employing different yarns upon the several series of carriers, the stripes forming the walls of a tubularly-formed product such as has been described, may be attractively varied in color or appearance as desired. My invention however provides for also varying the form or cross-section of the fabric produced; this being accomplished by diverting the carriers temporarily from their normal courses so as to produce different determined effects, as will now be described.

15 When the carriers a^1 on course a reach the point of intersection 6 with the adjacent course b , provision is made for diverting them, by means of a switch 15 as indicated, from their normal course a extending 20 across b , into course b ; so that instead of traveling around the warp threads extending through the openings in drive gears 10 a of the overlapping portions 8, they will travel (see Fig. 3) on the course b an equal 25 distance, to the point of intersection 7, where another switch 20 is provided to return them to their normal course a . The connecting warp threads at 10 a between courses a and b , being thus cut out, a flat 30 instead of tubularly formed product will result. Other warps may be introduced to give desired form to the edging stripes of the flat fabric.

As shown in the drawing, similar diverting switches 15, and returning switches 20, are provided at all the intersections 6 and 7 of the overlapping courses; a double returning switch 20 a being conveniently used at the common center of the circularly arranged series of courses, which switch is provided with a central opening forming the filler passage-way 5. Ordinary switch-operating means are provided as indicated for automatically setting these switches as 45 required to produce determined effects.

It will be readily understood that either tubularly-formed or flat stripe fabrics of uniform cross-section throughout may thus be readily produced as desired. In addition to this however a changing product of varied cross-section at different portions of its length such as indicated in Figs. 4, 5, and 6, may be produced on my improved machine. This is accomplished, by intermittently exchanging the travel of the carriers as indicated in Figs. 1, 2, and 3; the product being tubularly formed or flat according as the carriers are made to traverse the courses as indicated in Fig. 1, or as indicated in Figs. 2 or 3; and the edging stripes or beads of the flat sections being varied according as the carriers are diverted between courses a and b , or b and c , or c and d , or d and a . These latter changes are

more specifically indicated by the diagrammatic views Figs. 7 to 10, from which it will be seen that if differently colored yarns are employed on the several series of carriers these will successively appear on the edging stripes or beads of the different flat sections so as to produce variegated effects. The carriers on each course may travel in one direction only, thus merely turning the carrier threads around the linking warp threads without crossing them as in ordinary braiding operations.

The particular construction shown may obviously be readily modified without departing from my invention; as for instance by changing the number of tubularly linked courses employed, or the numbers of carriers employed in the different courses.

What I claim is:

1. A braiding-machine structure comprising a circularly linked series of tubular carrier courses each provided with a separate series of carriers traveling in one direction only thereon, and coöperating drive gears for all the carriers; each of said courses crossing each adjoining course at two points of intersection so as to form an overlap including two drive-gear centers, and the drive gears at said centers being provided with linking-warp thread openings.

2. A braiding-machine structure comprising a circularly linked series of tubular carrier courses each provided with a separate series of carriers traveling in one direction only thereon, and coöperating drive gears for all the carriers; each of said courses crossing each adjoining course at two points of intersection so as to form an overlap including two drive-gear centers, and the drive gears at said centers being provided with linking-warp thread openings; and switch mechanism for controlling the carrier movements at said points of intersection.

3. A braiding-machine structure comprising a plurality of carrier courses arranged in a circular series, separate series of carriers for said courses, and coöperating drive gears therefor; said courses intersecting each other so as to provide overlaps each of which includes race-circles of adjacent courses, and the drive gears of said race-circles being provided with linking-warp thread opening; and switch mechanism for cutting-out said race-circles from their respective courses comprising a double switch located at the center of said circular series of carrier courses.

4. A braiding-machine structure comprising a plurality of carrier courses arranged in a circular series, separate series of carriers for said courses, and coöperating drive gears therefor; said courses intersect-

ing each other so as to provide overlaps each of which includes race-circles of adjacent courses, and the drive gears of said race-circles being provided with linking-
5 warp thread openings; and switch mechanism for cutting-out said race-circles from their respective courses comprising a double switch located at the center of said cir-

cular series of carrier courses and provided with a warp thread opening.

In testimony whereof I affix my signature in presence of two witnesses.

ROBERT CARL RAHM.
